UNITED STATES PATENT OFFICE

110,897

DESIGN FOR A JUICE EXTRACTOR

Herbert C. Johnson, Wilmette, Ill.

Application January 12, 1938, Serial No. 74,224

Term of patent 14 years

To all whom it may concern:

Be it known that I, Herbert C. Johnson, a citizen of the United States, residing at Wilmette, county of Cook, State of Illinois, have invented a new, original, and ornamental Design for a Juice Extractor, of which the following is a specification, reference being had to the accompanying drawing, forming a part thereof.

I claim:

The ornamental design for a juice extractor, as shown.

HERBERT C. JOHNSON.
